Patented Nov. 12, 1918.

Proprietor;
Tunesaburo Akiyama.

UNITED STATES PATENT OFFICE.

TSUNESABURO AKIYAMA, OF ROCHESTER, NEW YORK.

DESIGN FOR A SOLDIER'S MAIL STAMP.

52,621.

Specification for Design.

Patented Nov. 12, 1918.

Application filed July 31, 1918. Serial No. 247,704. Term of patent 3½ years.

To all whom it may concern:

Be it known that I, TSUNESABURO AKIYAMA, a subject of Empire of Japan, residing at Rochester, in the county of Monroe and State of New York, have invented a new, original, and ornamental Design for Soldiers' Mail Stamps, of which the following is a specification, reference being had to the accompanying drawing, forming part thereof.

The figure is plan view of a soldier's mail stamp, showing my new design.

I claim:

The ornamental design for a soldier's mail stamp as shown.

TSUNESABURO AKIYAMA.
